UNITED STATES PATENT OFFICE.

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI.

AUGER.

Application filed August 9, 1926. Serial No. 128,083.

This invention relates to augers, and with regard to certain more specific features to earth augers of the type adapted to be cleared at intervals of earth, débris and the like.

Among the several objects of the invention may be noted the provision of an auger which is adapted to have certain members or jaws expanded for the purpose of dislodging bored out material, but which at the same time is adapted to positively prevent said members or jaws from loosening or expanding as the boring operation proceeds; an auger of the class described which holds said jaws more tightly as boring proceeds; a device of the class described which comprises but relatively few simple and rugged elements which can be readily and quickly assembled; and a device of the class described which is simple to manipulate in its applications. Other objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a left side elevation of the auger shown in locked, closed or boring position, certain portions being broken away, and shows in dotted lines an alternate retracted position of a locking sleeve;

Fig. 2 is a front elevation of Fig. 1, certain portions being broken away;

Fig. 3 is a horizontal section taken on line 3-3 of Fig. 2 but shows the sleeve rotated ninety degrees;

Fig. 4 is a horizontal section taken on line 4-4 of Fig. 2;

Fig. 5 is a bottom plan view of Fig. 2; and,

Fig. 6 is a view similar to Fig. 2 on a reduced scale showing the locking sleeve reTRACTING and the jaws of the auger opened or expanded for cleaning purposes.

Similar reference characters indicate corresponding parts throughout the several views of the drawings.

Referring now more particularly to Figs. 1 and 2 there is illustrated at the numeral 1 a shank upon which are cast or otherwise

formed three radially extending fins 3. A fourth fin 5, equal in depth to said fins 3 is also provided. The fin 5 carries a longitudinal leg 43 of a slot S. All of the fins 3 and 5 are preferably formed longitudinally of said shank 1.

The interior of the shank 1 is bored out to receive a suitable torque exerting member or stem 9 on the upper end of which is fastened a cross bar or wrench 11. The stem 9 is held in the socket of the shank 1 by a suitable fastening bolt 13, whereby torque may be applied to the shank 1 from the cross bar or handle 11.

Below the fins 3, 5, the shank 1 is formed as a semi-circular cylindrical portion 15, the radius of which is such as to align the outer surface of the said fins 3, 5, with the outer surface of the semi-circular cylindrical portion. The lower end of this semi-circular cylindrical portion 15 is formed with a matching lug 17 which functions in a manner to be described. In one quadrant of the circle which describes the surface of the partial cylinder 15, there is provided a notch 16 conforming to the shape of said lug 17. A flange 19 is provided at the lower end of the portion 15, and carries a dependent ear 21.

The ear 21 carries two lugs 23 adapted to cooperate with suitable openings in a stationary blade 25 and the blade 25 is held to the ear 21 by a suitable screw 27. The outer surfaces of the lugs 23 and the head of the screw 27 are preferably made flush with the outer surface of the blade.

The inner flat surface 29 of the semi-cylindrical or partial cylinder portion 15 is matched by the flat inner surface of a semi-cylindrical hinging member or partial cylinder 31. This hinging member 31 is formed to match with the portion 15 inasmuch as it has a notch 33 adapted to cooperate with the lug 17, and a lug 35 adapted to cooperate with said notch 16. It also has a flange 37 forming a continuation of said flange 19. The flange 37 carries a blade 26 similar to the blade 25. The fastenings for this blade are similar to those for blade 25 comprising lugs 23 and a screw 27 carried on another ear 21. The members 15 and 31 are held together in a relatively hinging manner by a hinge bolt 39, the head and nut of which are properly countersunk in the surfaces of the said members 15 and 31. It

may be seen from the above that the members 15 and 31 form a matched cylinder C having a lower flange F, that is, in their closed position. A cylindrical band of material 41 is formed on the portion 15 just under the shank 1. This band has an outer surface flush with the surfaces of the fins 3, 5, and with said cylinder C.

A tortuous bayonet slot or guide means S is provided in the fin 5 and the band 41. The vertical leg 43 of this slot S is formed in said fin 5, and the horizontal circular portion 45 thereof is formed in the band or belt 41. This horizontal circular portion 15 comprises a full-depth slot over an arc of 180 degrees (Fig. 3) and thereafter becomes gradually shallower over an arc of approximately 90 degrees. The complete length of the leg 45 of the slot S comprises substantially three quarters of a circle.

Slidably fitted over the fins 3, 5, and the continuing cylinder C, is a locking sleeve 47 which has formed therewith an inwardly projecting lug 49 adapted to slidably engage 25 the bayonet slot or guide means S throughout the length of said slot. The sleeve 47 preferably comprises a malleable casting, which when cast has had the lug 49 extending longitudinally, as shown by the 30 dotted lines in Fig. 2. By means of this method of manufacture the sleeve 47 may be slipped over the fins 3, 5, and cylinder C, the lug 49 aligned with the leg 43 of the slot S, and the lug 49 giving a blow so as to 35 turn it inwardly into said slot (see Figs. 2 and 3). The relative lengths of the fins 3, 5, the cylinder C, and the sleeve 47 are such that the cylinder 47 may be slipped upwardly along the said fins 3, 5, to entirely 40 clear the hinged cylindrical portion C or may be slipped downwardly to entirely and snugly jacket said cylindrical portion C. When the sleeve is positioned downwardly it rests on the flange F. It is evident from 45 the above that when the sleeve is in its upward retracted position, that the blades 25 and 26 may be relatively moved or hinged as shown in Fig. 6. When the sleeve 47 is put into its downward locking position, 50 then the blades 25, 26 must be in their closed position and are positively held in said position by the action of the sleeve 47 engaging the cylinder C (see Fig. 2). The manner in which the sleeve locks the blades is posi- 55 tive.

Another feature of the operation of this invention is that when the sleeve 47 is put into its lower locking position, then the sleeve may be turned so that the lug 49 travels around in the leg 45 of the slot S. The sleeve may be turned until said lug 49 engages the shallow portion of the slot. By this means the sleeve is wedged into locking position. Furthermore, the leg 45 of the slot S is cut in such a direction that

when boring takes place in a clockwise direction, then the drag of the earth on the sleeve 47 will tend to turn this sleeve tightly into its locking position. This means that the blades cannot accidentally come loose as 70 boring proceeds. Another feature of the sleeve 47 is that the hinging elements between the blade are protected from dirt, débris and the like during the boring operation. The shallow portion of the slot S is 75 positioned oppositely to the main mass of the hinging element 31 so that when the lug 49 rides in said portion then the sleeve 47 is drawn so as to push the element 31 up against the element 15, regardless of wear. 80 Tight blades are thus always assured while boring proceeds.

Figs. 1 and 2 illustrate how the cutting ends 51 of the blades are made, and how 85 they are given a set in order that the upper portions of the auger will not jam into the hole being bored.

In order to bore a hole an operator needs merely close the blades 25, 26, slip the locking sleeve down over the cylindrical portions C, turn said sleeve 47 counterclockwise, and proceed with the boring operation. When the blades are filled with earth or the like the auger is withdrawn, the sleeve 47 turned clockwise and retracted upwardly, whereupon the blades automatically move apart as gravity forces out the earth, or the blades may be pulled apart.

In view of the above, it will be seen that the several objects of the invention are 100 achieved and other advantageous results attained.

As many changes could be made in carrying out the above constructions without departing from the scope of the invention, it 105 is intended that all matter contained in the above description or shown in the accompanying drawings shall be interpreted as illustrative and not in a limiting sense.

I claim:

1. An auger comprising relatively hinged blade members cylindrically formed at the hinging portions therebetween, a locking sleeve adapted to slide over said hinging portions to lock said blades in closed position and adapted to slide therefrom, slotted guide means formed in one of the hinging portions and means on said sleeve adapted to slidably engage said slotted guide means.
2. An auger comprising relatively hinged blade members cylindrically formed at the hinging portions therebetween, a locking sleeve adapted to slide over said hinging portions to lock said blades in closed position and adapted to slide therefrom, slotted 125 guide means shaped to guide said sleeve in a predetermined movement, and a lug on said sleeve adapted to slidably engage said slotted guide means.
3. An auger comprising blade members, 130

- means for relatively hinging said blade members, a sleeve adapted to slide over the hinging means, said sleeve being adapted to hold said blade members in a predetermined position, guide means, and a lug on the sleeve adapted to slidably engage said guide means, said guide means having a restricted portion for engaging the lug to force said sleeve to tightly hold the blade members.
- 5 4. An auger comprising blade members, means for relatively hinging said members, a sleeve adapted to slide over said hinging means and thereby to hold said blades in a predetermined position, guide means having one leg thereof formed circularly with respect to the hinging means, and a lug on said sleeve adapted to engage the guide means such that when the lug is at the said circular portion the said blade members are held in 15 said predetermined position.
- 10 5. An auger comprising blade members, means for relatively hinging said members, a sleeve adapted to slide over said hinging means and thereby to hold said blades in a predetermined position, guide means having one leg thereof formed circularly with respect to the hinging means, a lug on said sleeve adapted to engage the guide means such that when the lug is at the said circular portion the said blade members are held in 20 said predetermined position, and a shallow portion in the circular portion of said guide means adapted to be engaged by the lug to wedge the sleeve.
- 25 6. An auger comprising blade members, means for relatively hinging said members, a sleeve adapted to slide over the hinging means and adapted to rotate with respect thereto, said sleeve being adapted to hold said blade members in a predetermined position when surrounding the hinging means, a bayonet guide means formed in said hinging means, a lug on the sleeve adapted to engage the guide means, said guide means being adapted to permit longitudinal movement of the sleeve on and off of the hinging means and to permit rotatable movement of the sleeve on said hinging means, whereby longitudinal movement of the sleeve is prevented, 30 said guide means having a shallow reduced portion therein adapted to be engaged by said lug whereby the sleeve is wedged 20 against the hinging means.
- 35 7. An auger comprising blade members, means for relatively hinging said members, a sleeve adapted to slide over the hinging means and adapted to rotate with respect thereto, said sleeve being adapted to hold said blade members in a predetermined position when surrounding the hinging means, a bayonet guide means formed in said hinging means having a longitudinal and a circular element, and a lug on the sleeve adapted to engage said guide means whereby the sleeve is adapted to be slipped from the hinging means when the lug is in the longitudinal element of the guide means and to be locked over the hinging means when the lug is turned into the circular element of the 40 guide means.
- 45 8. An auger comprising blade members, means for relatively hinging said members, a sleeve adapted to slide over the hinging means and adapted to rotate with respect thereto, said sleeve being adapted to hold said blade members in a predetermined position when surrounding the hinging means, a circular element, a lug on the sleeve adapted to engage said guide means whereby the sleeve is adapted to be slipped from the hinging means when the lug is in the longitudinal element of the guide means and to be locked over the hinging means when the lug is turned into the circular element of the guide means adapted to be engaged by said lug, whereby the sleeve is wedged 45 against the hinging portion.
- 50 9. An auger comprising blade members, means for relatively hinging said members, a sleeve adapted to slide over the hinging means and adapted to rotate with respect thereto, said sleeve being adapted to hold said blade members in a predetermined position when surrounding the hinging means, a bayonet guide means formed in said hinging means, a lug on the sleeve adapted to engage the guide means, said guide means being adapted to permit longitudinal movement of the sleeve on and off of the hinging means and to permit rotatable movement of the sleeve on said hinging means, whereby longitudinal movement of the sleeve is prevented, said guide means having a shallow reduced portion therein adapted to be engaged by said lug whereby the sleeve is wedged 55 against the hinging means.
- 55 10. An auger comprising relatively hinged blade members cylindrically formed at the hinging portion therebetween, a locking sleeve adapted to slide over said hinge portions to lock said blades in closed position, and to slide therefrom, a tortuous guide means formed in one of the members and a lug on said sleeve adapted to slidably engage said guide means.
- 60 In testimony whereof, I have signed my name to this specification this 6th day of August, 1926.

THEODORE BIRKENMAIER.
